UNITED STATES PATENT OFFICE.

BEAL C. FROMAN, OF EDWALL, WASHINGTON, ASSIGNOR OF ONE-THIRD TO JOHN L. WARD,
OF EDWALL, WASHINGTON.

RAILWAY-SWITCH.

No. 896,203.

Specification of Letters Patent.

Patented Aug. 18, 1908.

Application filed January 15, 1908. Serial No. 410,999.

To all whom it may concern:

Be it known that I, BEAL C. FROMAN, a citizen of the United States, residing at Edwall, in the county of Lincoln and State of Washington, have invented certain new and useful Improvements in Railway-Switches, of which the following is a specification.

The object of this invention is to provide novel improvements in railway switches and 10 the essential feature of the invention resides in the provision of means for preventing the switch rails from assuming an unauthorized position which might give rise to accident, or the like.

15 Another object of the invention is to provide means whereby the switch rails when once actuated to permit rolling stock to take the siding, will be locked in the position assumed thereby after being so actuated, and 20 automatically returned to the normal position thereof when the rolling stock has cleared the switch rails.

25 For a full understanding of the present invention, and the merits thereof, reference is to be had to the following description and to the accompanying drawings, in which,

Figure 1 is a top plan view of mechanism constructed in accordance with the invention; Fig. 2 is a transverse sectional view 30 taken on the line 2—2 of Fig. 1; Fig. 3 is a section taken on the line 3—3 of Fig. 1; Fig. 4 is a detail cross section taken on the line 4—4 of Fig. 1.

Like reference characters refer to like parts 35 throughout the description, and drawings.

Specifically describing the invention, and referring to the drawings the numeral 1 denotes the main rails of the track and the numerals 2 and 3 the switch rails, which are 40 arranged in the customary manner relative to the main rails and are of the same construction, generally speaking, as those switch rails which are now commonly in use. The normal arrangement of the switch rails is 45 such that the main track is closed to the siding, said switch rails being operable by a suitable switch bar attached thereto, said switch bar being adapted to be moved by a crank lever 5, the crank 6 of which is connected by a rod 7 to the bar 4. A coiled spring 8 is connected with the bar 4 in such a manner as to normally hold said bar at the limit of its movement toward the post 9 upon which the lever 5 is mounted.

55 The switch rail 2 is peculiarly mounted

upon the track in that it is adapted for a slight amount of vertical movement. For the above reason the switch rail 2 for a distance of a number of feet from its point is loosely supported upon the ties 10 of the 60 track but being braced by suitable braces 11 secured to said ties. Under normal conditions the switch rail 2 is held slightly above the ties 10 of the track by means of a spring 12 mounted in a suitable casing 13 and located beneath the rail 2. The spring 12 tends to force the rail 2 upwardly and to hold the latter so that it is spaced from the cross ties 10 but readily adapted to be forced 65 downwardly until supported rigidly by said 70 ties as when a weight is received upon the rail 2. The point 2^a of the rail 2 is adapted to interlock with the adjacent cross tie 10^c, the latter being formed with a recess 10^b, one side of the recess forming a shoulder 10^c 75 adapted to engage with the outer side of the switch point 2^a and thereby hold said switch point in such a position that the switch rails, which move together, are so related to the main rails 1 that a train traveling on the 80 main line may take the siding.

The advantages of the invention will appear more fully from the brief description of the operation thereof under actual conditions of service. Should it be desired that a 85 train on the main line take the siding, the lever 5 is operated, either manually or otherwise, in order to throw the switch rails into the proper position and against the tension of the spring 8 connected with the switch bar 4. 90 As soon as the front wheel of the engine or car on the main line is received upon the switch rails 2, it will be apparent that the compressible rail 2 will be depressed so that its base is supported by the ties 10 and this action will cause the point 2^a to be engaged by the shoulder 10^c of the recess 10^b and the switch rails will thus be locked in the position assumed thereby, even though the lever 5 is not held. Of course when the train has 95 passed onto the siding and the weight of the rolling stock is removed from the compressible switch rail 2 the latter will be raised slightly by the spring 12 and thus disengaged from the recess 10^b of the tie 10^a. As soon as the 100 switch joint 2^a is disengaged from the recess 10^b the spring 8 acts upon the switch rails to restore the latter to their normal position, the object being that under all conditions the 105 switch rails remain in said normal position 110

except when the rolling stock is to take the siding or is passing from the siding on to the main track. When the rolling stock passes from the siding to the main track the wheels thereof automatically force the switch to proper relation to the main rails and against the tension of the spring connected with the switch bar 4. In the actual use of the present invention there is no likelihood of the switch rails occupying an improper position and the action of the switch rails is automatic in returning to their normal position, by reason of the peculiar mounting and operation of the depressible rail 2.

Having thus described the invention, what is claimed as new is:

1. In a railway switch, the combination of main rails, switch rails, means normally holding the switch rails in a predetermined position, one of said switch rails being depressible, and means arranged to interlock with the depressible switch rail to hold the same in an adjusted position.
2. In a railway switch, the combination of main rails, switch rails, means normally holding the switch rails in a predetermined position, one of said switch rails being depressible, means arranged to interlock with the depressible switch rail to hold the same in an adjusted position, and means for automatically disengaging the depressible rail from the interlocking means aforesaid when downward pressure upon said switch is removed.
3. In a railway switch, the combination of main rails, switch rails, one of which is de-

pressible when weight is received thereupon, means for normally holding the switch rails in a predetermined position, means engageable upon depression of the depressible rail to hold the switch rails out of their normal position, and spring means coacting with the depressible switch rail to restore the switch rails to their normal position when downward pressure on the depressible rail is removed.

4. In a railway switch, the combination of main rails, switch rails, means for actuating the switch rails, means for holding the switch rails in a predetermined position, one of the switch rails being adapted for vertical movement, a member arranged to interlock with the vertically movable switch rail when the latter is depressed, and means for normally holding the depressible rail at the upper limit of its movement.

5. In a railway switch, the combination of main rails, switch rails, one of said switch rails being depressible, means for normally holding the switch rails in a predetermined position, means directly coöperating with the depressible switch rail on depression thereof to temporarily lock the switch rails out of their normal position when actuated, and automatic means for restoring the switch rails to their normal position.

In testimony whereof I affix my signature in presence of two witnesses.

BEAL C. FROMAN.

Witnesses:

ROBERT HAYNES,
WARD JESSEPH.
